SHEDDING DEVICE FOR DOBBIES

Hans Grossmann, Hongg near Zurich, Switzerland, assignor to Gebr. Staubli & Co., Horgen, Switzerland

Application July 20, 1931, Serial No. 552,041,
and in Switzerland September 17, 1930

8 Claims. (Cl. 139—66)

Dobbies are known in which the advancing and lagging (also called fluttering or flying and standing of the shafts) are brought about by relative angular movements of two swing levers carrying the same lifting knife. There are also dobbies in which for the same purpose, in the weaving of plain weaves, individual hooks can advance beyond the others.

According to the present invention, the fluttering is accomplished by interposing of levers between the dobbies and the shafts, which levers by means of cam guides produce an accelerating or retarding supplementary movement, so that the crossing of the warp threads, instead of occurring in one plane, is distributed amongst a plurality of superposed planes. The lever construction is such that the levers may differ in position at will from one shaft to another.

Three constructional examples of the invention are illustrated in the accompanying drawings, in which

Figures 1, 2 and 3 show the first example in side elevation in three different positions,

Figure 4 shows a plan of the devices in the position shown in Figure 1, and

Figure 5 shows a movement diagram of two shafts, which are equipped with levers according to the invention.

The dot-and-dash line shows the diagram of a normally moving shaft.

Figures 6 and 7 are side-elevations of the second and third example.

In Figures 1 to 4, *a* is a standing lever, rotatable about a pivot *b*, and swung to and fro by hooks *c*¹ and *c*² through the medium of a balance lever *d* in a known manner between the positions indicated by the lines *A* and *C*.

Between the standing levers *a* and the bars *e* leading to the jack levers, levers *f* (*f*¹, *f*² . . . *f*ⁿ) are interposed in any desired sequence, corresponding to the pattern. These levers *f* are loosely suspended from the pivots *g* on the standing levers *a*, and they each carry a pin *h*, on which the connecting bar *e* is hooked on. The peripheral curves of the levers *f* roll while raising the shaft upon rollers *i*, which are mounted loose upon a pivot *k* supported in a bracket *l*.

In Figures 1, 2 and 3, and also in the diagram of Figure 5, *A* denotes the initial position of the standing lever *a* and of the shafts, *B* the mid position and *C* the end position, when the shed is open. All the shafts begin to rise together (Fig. 1). Owing to the retarding supplementary movement produced by the lever *f*¹ the corresponding shaft at first lags behind the normally

suspended shaft, the difference becoming a maximum in the position *B*, and being compensated for by an acceleration of the movement in the second half. The shafts that are actuated by the levers *f*² are at first accelerated by the corresponding cam in the earlier part of their movement. The difference likewise reaches a maximum in the position *B*, shown in Figure 2, and these shafts then undergo a retardation, so that in the position *C*, shown in Figure 3, all the shafts are again at the same level. By these variations of shedding, different planes of crossing are accordingly obtained. The curvatures of the levers *f*¹ and of the levers *f*² may be formed in any desired manner.

It is therefore possible to employ more than two different sorts of levers and thereby to increase to any desired extent the number of planes of intersection. Similarly by suitable shaping the result can be obtained that individual shafts only begin to rise or fall after the normally suspended shafts, if required. The levers *f*¹, *f*² . . . *f*ⁿ admit of being readily substituted for one another, and employed in any desired sequence according to the pattern to be produced, in which case between two such levers a connecting bar of the same length as the connecting bars attached to the pins *h* can be directly hooked on to the pins *g* of a standing lever *a*. When such fluttering or separation is not wanted, all the connecting bars *e* are directly hooked on to the pins *g* on the levers *a*, all the intermediate levers *f* being omitted.

This device can be applied not only to new machines but also to old machines that are already in operation. If suitably constructed it is also applicable to hanging or suspended levers *a*.

The cam surfaces that produce the acceleration or retardation of the shafts, instead of being arranged on the levers *f* may be arranged on arms which are set upon the pivots *k* and *n*, and upon which by means of rollers, levers are allowed to run, which are supported in the manner illustrated for the levers *f* and which carry the connecting bars *e*.

Levers corresponding in their action to the levers *f* illustrated may also be interposed at another position in the connection of the dobbies with the shafts. Thus for example the lever *a* attached to the balance lever *d* itself admits of being constructed as such a lever, influenced by a sliding guide, or else such a lever may be fitted into the jack levers themselves.

An example of this last mentioned kind is

shown by Fig. 6. Here the connecting bar *e* is connected with the upper arm of a lever *o* to the lower arm of which a lever *f* is hooked on by means of a pin *g*. To said lever *f* two shaft-cords *p* are attached. By the pull of the shaft *u* the curved upper edge *s* of the lever *f* is maintained in contact with a stationary roller *r*.

When the connecting bar *e* is drawn towards the right the point *h* receives an alternately accelerated and retarded movement by means of the curvatures *s* passing below the rollers *r*. By suitably choosing the form of the lever edge *s* similar differences in the course of movement of vicinal levers can be obtained as with the curve-shaped levers *f¹*, *f²* of the first described example.

In the modified form according to Fig. 7 which represents the device in its middle position, levers *f¹*, *f²* are pivoted on a pin *g* mounted on a shortened standing lever *a* and have their curved ends directed upward so as to extend below a series of rollers *i*, the common shaft of which is mounted in brackets *t* wherein it may be adjusted in vertical direction. The connecting bars *e* are hooked on to these levers by means of pins *h*. (For sake of clearness, the pin *h* on the lever *f¹* the associated connecting bar *c*, jack levers *j¹* and *j²* and shaft *u* only are shown in the drawing). The jack shafts *j¹* and *j²* are of well known construction and are disclosed in U. S. Patent No. 1,514,873. A third lever, *f³*, is made without curvature and serves only to connect a lever *a* with the associated connecting bar *e* to transmit thereto an ordinary uniform movement. Obviously the arrangement of the various levers *f* (*f¹*, *f²*, *f³* . . .) can be easily adapted to the special requirements of each singular case of use, viz. for instance to the kind of the material to be used, to the pattern to be produced.

What I claim is:

1. A shedding device for dobbies, comprising shafts and levers interposed between the dobbies and its shafts, means adapted to impart oscillatory movements to these levers, cam guides in such relation to said levers as to produce an accelerating or retarding supplementary movement of the shafts during the oscillatory movement of said levers.

2. A shedding device for dobbies, comprising shafts and levers interposed between the dobbies and its shafts, dissimilarly curved portions on these levers, guiding members adapted to coat with said curved portions and means for imparting reciprocating movements to said levers, relatively to said guiding members.

3. A shedding device for dobbies, comprising shafts and levers interposed between the dobbies and its shafts, the pivots of these levers being mounted in bearings adapted to perform a reciprocating movement, dissimilar cam guides on said levers, stationary guiding members arranged in the reach of these cam guides, jack-levers carrying the shafts, members connected on one side with said jack-levers and on the other side with the first mentioned levers in such a manner as to hold the cam guides of the levers in contact with said guiding members by the weight of the shafts as the levers move.

4. A shedding device for dobbies, comprising shafts and standing levers adapted to perform a reciprocating motion, intermediate levers suspended from such standing levers, connecting bars hooked on said intermediate levers outside their axis of oscillation, a jack-lever connected with each of said connecting bars, curvatures on

said intermediate levers, guiding members in reach of these curvatures, these curvatures being held in contact with said guiding members during the reciprocating movements of the standing levers by means of the draft exerted by the connecting bars in such a manner that, according to the form of the curvatures, said connecting bars and therewith the dobbey shafts receive alternately an accelerating and retarding supplementary movement relatively to the movement of the axis of rotation of the intermediate levers.

5. A shedding device for dobbies, comprising shafts and standing levers adapted to perform an oscillating movement, bars connected with the shafts, intermediate levers suspended from a predetermined number of said standing levers, said bars being pivotably connected with such intermediate levers outside their axis of rotation on said standing levers, peripheral curves of different forms on said intermediate levers, stationary guiding members in the reach of said curves in such relation thereto that during the movement of the standing levers said peripheral curves pass in contact with said members imparting thus a different movement to connecting bars connected with intermediate levers having different peripheral curves, the relative positions of the axis of rotation of the intermediate levers on the standing levers and the points of connection of the connecting bars on said levers being such that the intermediate levers can easily be changed from one standing lever to another and that any of said connecting bars, with unaltered length and without changing the basic position of the dobbey shafts, can be optionally suspended either from the intermediate levers or directly from the standing levers.

6. A shedding device for dobbies, comprising a series of connecting members adapted to perform a reciprocating motion, levers pivotably mounted on horizontal pivots and connected each to one of said connecting members, a shaft connected with each of these levers, a second lever inserted between a determined number of said levers and the associated shafts and suspended from said levers, a guiding member above each of said suspended levers, a peripheral curve on the upper edge of these levers adapted to be held in contact with said guiding member by the weight of the associated shaft and to impart to this an alternately accelerated and retarded movement when the corresponding upper lever is actuated by the connecting member, said peripheral curves being different on two vicinal levers.

7. A shedding device for dobbies, comprising a series of standing levers adapted to perform reciprocating movements, an intermediate lever pivotably mounted on each of said standing levers, a connecting bar pivotably connected with each of said intermediate levers, jack levers connected with the other end of said connecting bars, different peripheral curves on a determined number of said intermediate levers, a stationary guiding member for each of such curves, each curve being held in contact with a guiding member during the movement of the standing lever supporting the intermediate lever and so formed that as the standing lever moves, the point of connection located on said intermediate lever of the connecting bar leading to the jack lever undergoes a supplementary movement which is dependent upon the shape of the curve.

8. A shedding device for dobbies, comprising a series of standing levers adapted to perform a swinging motion at predetermined moments,

jack-lever connected with each of these standing levers, a bar forming part of this connection, intermediate levers between such connecting members and the associated standing lever having their axis of rotation on this standing lever, different curvatures on a determined number of said intermediate levers, guiding members in such a position relatively to such intermediate levers that the curvatures thereon are held in contact 10 with said guiding-members by the draft of the

connecting-members as the associated standing levers move, the shafts connected with such intermediate levers receiving thus different speed according to the different curvatures on the intermediate levers, other of said connecting bars being connected with the associated standing levers in such a manner as to receive an uniform movement as these standing levers move.
